US0D1054452S

(12) **United States Design Patent** (10) Patent No.: **US D1,054,452 S**
(45) Date of Patent: ** Dec. 17, 2024

(54) **DISPLAY SCREEN OR PORTION THEREOF WITH ICON**

(71) Applicant: **Apple Inc.**, Cupertino, CA (US)
(72) Inventors: **Alan C. Dye**, San Francisco, CA (US); **Aurelio Guzmán**, San Jose, CA (US); **Raymond Sepulveda**, Portland, OR (US); **Aled Williams**, San Francisco, CA (US); **Christopher Wilson**, San Francisco, CA (US); **Chun Kin Minor Wong**, Cupertino, CA (US)

(73) Assignee: **Apple Inc.**, Cupertino, CA (US)

(**) Term: **15 Years**

(21) Appl. No.: **29/859,492**

(22) Filed: **Nov. 10, 2022**

Related U.S. Application Data

(63) Continuation of application No. 29/831,516, filed on Mar. 21, 2022, now Pat. No. Des. 969,869, which is a continuation of application No. 29/763,028, filed on Dec. 21, 2020, now Pat. No. Des. 949,916, which is a continuation of application No. 29/649,917, filed on Jun. 4, 2018, now abandoned.

CLAIM

The ornamental design for a display screen or portion thereof with icon as shown and described.

DESCRIPTION

FIG. 1 shows a display screen or portion thereof with icon showing our new design; and,
FIG. 2 shows another embodiment thereof.

The peripheral dashed broken lines illustrate a display screen or portion thereof, and form no part of the claimed design.

1 Claim, 1 Drawing Sheet
